(57) **CLAIM**

The ornamental design for a webcam privacy shield, as shown and described.

DESCRIPTION

FIG. 1 is an isometric view of an open webcam privacy shield showing my new design;

FIG. 2 is an isometric view of a closed webcam privacy shield thereof;

FIG. 3 is a front view of the open webcam privacy shield of FIG. 1;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an isometric view of the webcam privacy shield shown in a configuration of use.

The broken lines in the drawings depict environmental structure, specifically an unclaimed computer in FIG. 9, and forms no part of the claimed design.
